BRAUN TUBE

Wolfram Uhlmann, Berlin, Germany, assignor to
 C. Lorenz Aktiengesellschaft, Berlin-Tempelhof, Lorenzweg, Germany, a company

Application February 8, 1938, Serial No. 189,301
 In Germany February 11, 1937

2 Claims. (Cl. 250—155)

The present invention relates to Braun tubes, and particularly to improvements in the system which produces the electron beam in such tubes.

The individual electrodes of the cathode ray producing system in Braun tubes employed in the practice are attached to supporting rods of insulating material which are arranged in parallel to the axis of the tube. These rods are fixed to the stem of the tube in any manner and carry the entire electrode system. Each individual electrode is attached to the supporting rods by clip rings in order to prevent axial displacement thereof. It is necessary that each individual electrode is concentrically positioned in the mounting operation since the reliability of the tube is highly dependent upon this requirement. The structure of television tubes hitherto known has not been well adapted for series production since utmost accuracy and conscientiousness must be required from each workman in charge of the mounting operation. It is therefore not astonishing when under such circumstances the individual tubes of a manufacturing series present different properties.

The invention proposes quite new ways for mounting the electrode of tubes above referred to. According to the invention, each electrode is a circular-symmetric body and these bodies are mounted one upon the other by the agency of intermediate insulating rings whereupon an axial tension is applied to the assembly so as to obtain a uniform body.

Cathode ray producing systems are known according to which all electrodes are mounted in an insulating body of tubular shape. This body is provided with shoulders onto which the electrodes are clamped. However, the manufacturing of such complicated insulating members is extraordinarily difficult, whereas the present invention employs simple rings which are easily to be produced.

The present invention will be more readily understood from the following description taken in conjunction with the accompanying drawing, which shows a cross section through one embodiment of the invention.

A number of supporting rods 2 are fixed in a ring 1 which is clamped around the stem A of the tube. These supporting rods carry an annular base plate 3 adapted to support the entire electrode system. A ring 4 of insulating material which is covered by a metal cap 5 is first brought into position in the base plate 3. The inner surface of the cap 5 carries a tubular member 6, the function of which is hereinafter more

closely described. The two members 5 and 6 form a Wehnelt cylinder. Two insulating rings 8 and 10 together with an intermediate metal disc 9 are then placed on the top of the cap 5. The disc 9 which is provided with a central bore 5 serves as suction electrode. The insulating ring 10 in turn carries a further electrode 11 likewise having a central hole. An electron lens cylinder 12 is placed directly on the top of the electrode 11 and is provided with a diaphragm 13. The inner surface of a further insulating body 14 serves for centering the electron lens cylinder, while its outer surface is adapted to centre an anode cylinder 15 which encompasses the electron lens cylinder 12. This insulating body 14 15 is provided with a shoulder forming a seat for the anode cylinder 15. In this state, the entire electrode system is adapted to be assembled to one structural unit. This is accomplished by means of clamping rods, e. g. three thereof, which are 20 fixed to the anode cylinder 15 and extended through the lower base plate 3 where the required tension may be applied thereto. For the purpose of securing accurate concentrical seat for the different electrodes, the insulating rings are 25 provided with a special cross sectional area, instead of having their major surfaces in parallel with one another. Nevertheless, also plane insulating rings may be employed, provided that the edges of the electrodes are equipped with hooklets. 30

The cap 5 and the tubular member 6 act as a Wehnelt cylinder as mentioned above. The tubular member 6 is welded to the cover 5 and adapted to receive the cathode which comprises a small insulating tube 16, the upper end of 35 which carries the metallic support for the electron emitting layer 17. This rod-shaped cathode is mounted in a member 18 of an insulating material, or of a metal of low thermal conductivity. The cathode and the member 18 form one unit 40 which is passed into the tube 6 and fixed in axial direction. The cylindrical portion of the cap electrode 5 may be provided with one or more apertures, so as to permit the correct adjustment of the axial interspace between the cap and the 45 member 17 to be observed. It is also possible to provide the body 18 with a projecting collar as a seat for the cathode so as to compulsorily secure the correct interspace between the face of the cathode and the adjacent electrode after this 50 body has been brought into position. It will be readily understood that this arrangement requires that the distance between the face of the cathode and the collar has been exactly defined in manufacturing the cathode, and that the tubu- 55

lar member 6 has a predetermined length. In such cases an adjustment of the cathode in the axial direction becomes superfluous. This new arrangement presents essential advantages over the known cathode structures, since the old supporting lugs for the cathode are omitted and the subsequent centering measures have been rendered superfluous.

10 The lead-in conductors to the individual electrodes are carried through slots in the insulating rings as far as these cannot be applied from the outer side of the structure.

What is claimed is:

- 15 1. In a Braun tube, a cathode ray producing system, comprising a rod-shaped cathode, a circular symmetric member therefor, having a shoulder, a circular control electrode, further electrodes likewise of circular symmetric shape, insulating rings adapted to separate the individual electrodes from one another and having cross sectional shapes of different diameters so as to provide concentrical seats therefor, means for combining said electrodes and insulating

rings to one unit, and a diaphragm, said shoulder being adapted to define the interspace between the electron emitting face of the cathode and said adjacent diaphragm when the cathode and its holder are inserted in the circular control electrode.

2. A Braun tube comprising an annular ring of insulating material having a portion of reduced diameter, a metal cylindrical cap therefor containing a metal tube forming with said cap a Wehnelt cylinder, an electron emitter within said cylinder, a plurality of electrodes superimposed on said cap and insulated therefrom and from one another by insulating rings, a tubular insulating body having internal portions of different diameters to engage respectively said cap and said electrodes, a tubular anode encircling said body and fixed to the upper end thereof and means for clamping said anode to said annular ring first mentioned to hold all of said parts together in a single unit.
